[57] CLAIM

The ornamental design for a mat for developing hand-to-eye coordination in infants, as shown and described.

DESCRIPTION

FIG. 1 is a top perspective view of a mat for developing hand-to-eye coordination in infants showing my new design;

FIG. 2 is a front elevational view thereof, the rear being a mirror image of that shown, except for the air valve;

FIG. 3 is a right side elevational view thereof, the opposite side being a mirror image of that shown;

FIG. 4 is a top plan view thereof; and,

FIG. 5 is a bottom plan view thereof.

FIG. 1

FIG. 2

FIG. 3

FIG. 4

FIG. 5
